UNITED STATES PATENT OFFICE.

BERNARD E. O'HAGAN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 14, 1924. Serial No. 743,524.

To all whom it may concern:

Be it known that I, BERNARD E. O'HAGAN, a citizen of the United States, residing at Swissvale, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus of the type comprising train carried governing means controlled by energy received from the trackway. More specifically my present invention relates to the trackway portion of such apparatus.

15 I will describe one form and arrangement of apparatus embodying my invention, and will then point out the novel features thereof in claims.

The accompanying drawing is a diagrammatic view showing one form of apparatus embodying my invention.

20 Referring to the drawing, the reference characters 1 and 1^a designate the track rails of a stretch of railway track. These track rails are divided, by means of insulated joints 2, into a plurality of successive track sections, of which only one complete track section A—B is shown in the drawing.

25 Each track section is provided with a track transformer designated by the reference character T with an exponent corresponding to the location and having a secondary winding 5 connected across the rails adjacent the right hand end of the corresponding section. An impedance 6 is interposed between secondary 5 of each track transformer T and one rail, 1^a, of the associated section in the usual manner. The primary 4 of each track transformer is constantly supplied with alternating current from some suitable source such as an alternator M, over line wires 3 and 3^a.

30 Each section is also provided with a track relay designated by the reference character R with a suitable exponent, which relay is connected across the rails adjacent the entrance end of the associated section. These track relays may be used to control traffic governing apparatus not shown in the drawing in any desired manner.

35 Means are also provided for supplying section A—B with train controlling loop

current which, in the present disclosure, 55 flows through the two rails of the section in parallel. For this purpose I connect two impedances 10 and 13 across the rails adjacent the left hand and right hand ends respectively, of the section. The immediate 60 source of this loop current is a loop transformer L' having a secondary winding 8 the terminals of which are constantly connected with the mid points of impedances 10 and 13, respectively. The primary 7 of 65 transformer L' is supplied with alternating current from line wires 3 and 3^a over a front contact 9 of track relay R^B. It is therefore plain that when relay R^B is energized, alternating loop current is supplied 70 to the rails of section A—B throughout their length from transformer L'.

The apparatus thus far described is suitable for co-operation with train carried governing means so arranged that when the 75 train occupies a stretch of track which is being supplied with loop current a less restrictive indication is received on the train but when this supply is discontinued, a more restrictive indication is received on the 80 train. In at least one form of apparatus arranged to co-operate in this manner the loop current in the track rails controls the train carried mechanism through the medium of a receiving device carried on the 85 train in inductive relation with the track rails.

Under some conditions, as when the track sections are very long or the ballast resistance is very low, a portion of the loop current leaks away from the rails at or near one end of the section, traverses the ground instead of the track rails, and returns to the rails at or near the other end of the section. As a result the magnitude of the loop current is less near the center than at the ends of the section. In some cases this condition may become so exaggerated as to render the operation of the train carried mechanism unreliable because the energy transferred to 90 this mechanism by the receiving devices is not sufficient to operate the mechanism when the train is in the middle of the section.

In order to overcome this undesirable 105 condition I provide two impedances 11 and 12 similar to impedances 10 and 13 and connected across the rails at spaced points be-

tween impedances 10 and 13. I also provide an auxiliary loop transformer L^2 having a primary winding 7 connected in parallel with the primary winding 7 of transformer 5 L' and having the terminals of its secondary 8 constantly connected with the mid points of impedances 11 and 12, respectively.

It follows that when transformer L' is 10 supplying loop current to the rails of the section between impedances 10 and 13, transformer L^2 also supplies loop current to the rails between impedances 11 and 12. The points of connection of impedances 11 15 and 12 and the magnitude of the current delivered by transformer L^2 are so chosen that when relay R^B is energized the total loop current at any point in the section is always of sufficient magnitude to insure reliable operation of the train carried mechanism.

Although I have herein shown and described only one form of trackway apparatus embodying my invention, it is understood 25 that various changes and modifications may be made therein within the scope of the appended claims without departing from the spirit and scope of my invention.

Having thus described my invention, what 30 I claim is:

1. In combination, a stretch of railway track, and means for simultaneously supplying train controlling loop current to the two rails of said stretch in parallel through 35 out the same portion of the stretch from two sources.

2. In combination, a stretch of railway track, means for supplying train controlling energy to the two rails in parallel between two points in the stretch, and other 40 means for simultaneously supplying train controlling energy to the two rails in parallel between two points at least one of which is between said two first mentioned 45 points.

3. In combination, a stretch of railway

track, means for supplying train controlling energy to the two rails in parallel between two points in the stretch, and other means for simultaneously supplying train controlling energy to the two rails in parallel between two points both of which last mentioned points are between said two first mentioned points.

4. In combination, a stretch of railway 55 track, a train controlling circuit for said stretch including the rails in parallel between two spaced points and the secondary of a first transformer, a second train controlling circuit for said stretch including the secondary of a second transformer and the rails in parallel between two other points both of which are located between said two first mentioned points, and means for simultaneously supplying energy to the primaries 60 of said first and said second transformers.

5. In combination, a stretch of railway track, a first pair of impedances connected across the rails at spaced points in the stretch, a second pair of impedances connected across the rails at spaced points between said first pair of impedances, a source of energy connected with the mid points of said first pair of impedances, and a second source of energy connected with the mid 70 points of said second pair of impedances.

6. In combination, a stretch of railway track, a first pair of impedances connected across the rails at spaced points in the stretch, a second pair of impedances connected across the rails at spaced points between said first pair of impedances, a transformer having a secondary winding connected with the mid points of said first pair of impedances, a second transformer having a secondary winding connected with the mid points of the second said pair of impedances, and means for at times simultaneously supplying energy to the primary of both said 80 transformers.

In testimony whereof I affix my signature.
BERNARD E. O'HAGAN.
